UNITED STATES PATENT OFFICE.

THOMAS J. BROWNE, OF OLDHAM, NOVA SCOTIA, CANADA.

SLIDING GATE.

1,277,844.

Specification of Letters Patent. Patented Sept. 3, 1918.

Application filed March 27, 1916. Serial No. 87,065.

To all whom it may concern:

Be it known that I, THOMAS J. BROWNE, a subject of the King of England, residing at Oldham, in the county of Halifax, in the 5 Province of Nova Scotia and Dominion of Canada, have invented certain new and useful Improvements in Sliding Gates, of which the following is a specification.

This invention has relation to certain new 10 and useful improvements in gates and it contemplates, primarily, the provision of a novel form of gate and supporting means therefor, whereby the gate may be easily and quickly operated with but little exertion 15 on the part of the operator and which consists of but a few simple parts whereby it is not likely to get out of order.

A further object of my invention is to provide a device of the type in question that 20 is extremely simple in construction, strong and durable, and highly practical from both the standpoint of the user and the standpoint of the manufacturer; and which, it is believed, may be manufactured at a 25 paratively low cost.

Various other objects and advantages will become apparent during the continuance of the following description.

These objects are accomplished by such 30 means as are shown in their preferred form in the accompanying drawings, described in the following specification and then more specifically pointed out in the appended claim.

35 In the accompanying drawings wherein like characters designate like parts throughout the several views:

Figure 1 is a view in front elevation showing my invention, as in its preferred embodiment, the gate proper being in a partly extended position;

Fig. 2 is a view in section taken on line 2—2 of Fig. 1;

Fig. 3 is a view in section taken on line 45 3—3 of Fig. 1; and

Fig. 4 is a fragmentary view of the gate and gate frame, showing more clearly the relative position of the members.

In the drawings, A designates a suitable 50 support in connection with which my invention has been shown, but it is to be fully understood that I am not limited to this specific application, since the gate may be advantageously used in connection with 55 other types of supports, within the discretion of the user.

10 and 11 designate relatively spaced upper and lower track members that carry suitably curved arms 12 and 13 that have connection with the support A as designated 60 at 14. At their inner ends, tracks 10 and 11 are connected by means of a member 15 that also carries a suitably curved arm 16 for connection with the support A, as at 17. In the present embodiment, the track ways are 65 formed integral with connecting member 15 and are preferably constructed of a length of piping or other material, substantially circular in cross section, whereby the tracks present opposed faces of substantially convex configuration. The purpose of this construction will subsequently appear.

At their forward ends, tracks 10 and 11 are slightly reduced as at 18 and they are connected by spaced vertically disposed stop 75 members 19 and 20 whose extensions 21 fit the side of the reduced portions 18, as clearly illustrated in Fig. 4. After the arrangement of the parts in this position, a suitable fastening member, such as shown at 22 may 80 be passed through the extensions 21 and the reduced portion 18, thereby insuring a completely rigid structure.

The gate structure of the present embodiment, consists of a suitably disposed frame 85 23 covered by a section of reticulated material 24, such as wire mesh, the same operating between stop members 19 and 20, as illustrated in Fig. 4. At its rear end, frame 23 carries relatively spaced hanger bearings 90 25 and 26 that in turn support guide wheels 27 and 28 which have circumferential grooves fitting the opposed faces of tracks 10 and 11. At its forward end, frame 23 carries a vertically disposed stop 29 that 95 projects laterally thereof, as in Fig. 4, and which is designed to abut against stops 19 and 20 to limit the inward movement of the gate structure, as is obvious.

I also provide the lower track 11 with a 100 supporting bearing 30 adjacent its forward end that carries a supporting roller 31 which has its circumferential grooved face fitting the lower frame member of the gate in order to support the latter in its true plane, at all 105 times. The rollers 27 and 28 serve to properly support the gate, at all times but by providing the additional supporting roller 31, it is apparent that the strain upon the other rollers, as well as the hanger bearings 110 25 and 26 is materially relieved. This construction not only insures the longevity of

the hanger bearings 25 and 26 but also serves to retain the gate in its true plane, as above stated and prevents the usual sagging thereof.

- 5 From the foregoing, it is believed that the advantages and novel features of my invention will be readily understood and, therefore, further detail description is deemed unnecessary.
- 10 In reducing my invention to practice, I find that the form referred to herein as the most practical and preferred embodiment of my invention, is the most efficient, but realizing that certain conditions will necessarily vary in concurrence with the adoption of my device, I desire to emphasize the fact that various minor changes in the details of construction and in the proportion of parts may be resorted to when required, 20 without sacrificing any of the advantages of my invention, as defined in the appended claim.

Having thus fully described my invention, what I claim as new and desire to secure by Letters Patent is:—

25 In combination, a support, a member bent to provide upper and lower parallel track

elements and a vertical element connecting the rear ends of the track element, said track elements having their outer ends reduced, 30 transversely spaced stop members having lateral extensions overlapping the reduced ends of the track elements and secured thereto, laterally extending arms connecting the track elements and said vertical element to the support, a gate disposed to operate between the transversely spaced stop members, wheels at the rear end of the gate to travel upon the track elements, said gate having a laterally projecting member at its forward end to close the space formed between the transversely spaced stop members and engage the latter and limit the inward sliding movement of the gate, and a roller disposed upon the forward end of the lower track 40 element to act jointly with the wheels at the rear end of the gate to hold the latter in proper position.

In testimony whereof I affix my signature in presence of two witnesses.

THOMAS J. BROWNE.
